UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

INSULATED RAIL-JOINT.

1,369,225.

Specification of Letters Patent. Patented Feb. 22, 1921.

Application filed October 22, 1919. Serial No. 332,360.

To all whom it may concern:

Be it known that I, CLARKSON A. DISBROW, citizen of the United States, residing at New Rochelle, in the county of Westchester and State of New York, have invented certain new and useful Improvements in Insulated Rail-Joints, of which the following is a specification.

This invention relates to means for insulating rail joints and has particular reference to a novel rail supporting and insulation holding means effecting economies in the amount of insulation employed and its maintenance under traffic and load conditions.

A primary object of the invention is to provide, in an insulated rail joint, a construction which permits the use of a minimum amount of insulating material without impairing the electrical function of the joint and at the same time providing for interlocking the fiber with the joint bar in such a manner that it is effectually held against displacement. Also a support of the rail head from the joint bar is accomplished in such a manner as to appreciably relieve the fiber or insulation from crushing strains particularly adjacent the rail ends where the fiber usually is subjected to the greatest strain and wear so as to cause failure while the remainder of the fiber or insulation is in good serviceable condition.

The particular construction and combination of parts which permit the attainment of the desirable objects above stated are necessarily susceptible of embodiment in different forms of construction without departing from the scope of the invention, but certain preferred and practical embodiments are shown in the accompanying drawings, in which Figure 1 is an end view of a rail joint fitted with the improvements contemplated by the present invention, the view showing the rail in section and the upper part of one of the splice bars cut away to show the mounting of the insulated rail supporting pin.

Fig. 2 is a side elevation of the joint shown in Fig. 1 with a part of the top of the joint bar and head fiber broken away to expose the insulated rail supporting insert or pin adjacent the rail end.

Fig. 3 is a top view of the upper part of the joint bar with the head fiber fitted thereon and a pair of the rail engaging inserts or pins shown at locations adjacent the meeting ends of the rails.

Fig. 4 is a top view of the rail joint bar showing a modification wherein the head fiber is intended to closely embrace the upper projecting metal of the rail engaging insert or pin and the insulating cup for the pin disposed entirely below the head fiber.

Fig. 5 is a detail view of the bar shown in Fig. 4 partly in section on the line 5—5 of Fig. 4.

Figs. 6 and 7 are respectively cross sectional and elevational views of a joint construction wherein the rail engaging metal inserts or pins are fitted in the head or foot of the bar and interlocked with head or base pieces of insulation.

Like references designate corresponding parts in the several figures of the drawings.

The insulation fittings, and rail supporting means, comprising the present invention are necessarily adaptable to different types of rail joints and different forms of joint bars without in any way departing from the purposes or objects of the invention. The distinctive feature of the latter resides in an insulation plate, of fiber or other acceptable insulating material, fitting a rail supporting face of the joint bar and interlocked with a metal rail supporting insert or pin projecting from the joint bar and not only constituting a metal-to-metal bearing support for the rail head but also a locking means for holding the insulation plate locked against displacement longitudinally or laterally. This combination of features accomplishes the dual function referred to, namely that of permitting the use of a minimum amount of insulation and also appreciably relieving the latter of the crushing strains from the rail head.

To illustrate the distinctive feature referred to there is shown in Fig. 1 of the drawings a rail joint including the rail R, and the joint bars 1—1 and each of these joint bars is provided, preferably in a location adjacent the end of each rail of the joint, with a seat or socket 2 drilled or otherwise suitably formed within its upper edge

portion. Each of these seats or sockets 2 is adapted to receive therein a metal pin or stud 3 constituting a metal rail supporting insert projecting above the top surface of the joint bar and adapted to have a metal-to-metal bearing supporting contact with the under side of the rail head. To provide a thorough insulation of this pin or stud 3 from the metal joint bar the same is preferably nested within an insulating cup 4 made of one or more pieces of insulating material and which cup is fitted within the seat or socket 2 so as to solidly rest on the bottom of the latter and to entirely surround the pin or stud, thereby preventing short circuiting between the pin or stud and the joint bar.

As above indicated the metal inserts 3 are preferably arranged in the head of the joint bar adjacent the rail ends to provide metal supports for the rail heads in the locations where the greatest strains and pressure is usually imposed upon the head fiber or insulation employed in the joint, and according to the present invention this head fiber or insulation designated by the numeral 5 is interposed between the head of the joint bar and the undersides of the rail heads, so as to be used in combination with the rail supporting metal inserts to insure a thorough head insulation for the joint throughout the entire length thereof. A feature of practical importance in connection with the use of the insulation plate 5 which is usually termed the head fiber or head piece of insulation is to have said insulation plate interlocked directly with said projecting metal inserts. This may be simply and substantially effected by forming the said insulation plate with keeper openings 6 at the locations where the inserts occur so that the latter will project through the said keeper openings 6 and thus become fiber locking pins or studs which positively prevent movement of the insulation plate either longitudinally or laterally. Thus the insulation plate will not be disturbed from its position by relative movement between the rails and joint bars nor subject to wear by the friction incident to such relative movement. Furthermore, it will be observed that the locking of the insulation plate by the metal insert is so positive as to entirely obviate the necessity of having the insulation engage with the joint bolts for locking purposes, and for that reason a comparatively small and narrow strip or plate of insulation may be used for the head piece of the rail joint, as shown in Figs. 1 and 2 of the drawings.

In Figs. 1, 2 and 3 the insulating cups 4 for the metal inserts are shown as projecting through the keeper openings 6 of the fiber head piece, but as illustrated in Figs. 4 and 5 of the drawings the said insulating cup

may terminate flush with the top of the joint bar and the insulation plate 5 formed with openings which fit the metal inserts sufficiently close to maintain a proper insulation.

By way of illustrating the range of modification which may be resorted to in carrying forward the invention there is shown in Figs. 6 and 7 of the drawings the application of the invention not only to a head piece of insulation for the head of the bar but also to a base piece 7 of insulation interposed between the foot of the bar and the rail flange. In this use of the invention the rail engaging pin or stud designated by the numeral 8 is nested in an insulating cup 9 seated in a socket at the foot of the bar and this insulated pin or stud projects through an opening in the base piece of insulation 7 to lock it in position.

Other modifications will be apparent to those familiar with the art and it will be understood that changes in the form, proportion and minor details of construction may be resorted to without departing from the spirit or scope of the appended claims or sacrificing any of the advantages of the invention.

I claim:

1. In a rail joint, a splice bar having an insulated rail engaging projection and an insulation plate interlocked with said projection.
2. In a rail joint, a splice bar having an insulated metal rail engaging projection and an insulation plate interlocked with said projection.
3. In a rail joint, a joint bar having an insulated metal insert projecting therefrom and an insulation plate interlocked with said metal insert.
4. In a rail joint, a joint bar having an insulated metal insert projecting above its head and an insulation plate interlocked with said insert.
5. In a rail joint, a splice bar having a plurality of inset rail engaging projections and an insulation plate interlocked with said supports.
6. In a rail joint, a joint bar having a plurality of inset insulated rail engaging projections and an insulation plate interlocked with said supports.
7. A rail joint, including the rails, the joint bar, an insulated rail engaging member projecting from the bar adjacent each rail end and an insulation plate interposed between the bar and the rail head and interlocked with said rail engaging member.
8. A rail joint including the rails, a joint bar, an insulated metal rail engaging member projecting beyond the bar adjacent each rail end and an insulation plate interposed between the bar and the rail and directly interlocked with said rail engaging member.

9. A rail joint including the rails, a joint bar, an insulated metal rail engaging pin fitted to the bar and projecting therefrom adjacent each rail end and an insulation plate interposed between the bar and the rail and having a keeper opening interlocking with said pin.

In testimony whereof I hereunto affix my signature in the presence of two witnesses.

CLARKSON A. DISBROW.
